UNITED STATES PATENT OFFICE.

WITSEL R. DE CAMP, OF ROSELAND, NEW JERSEY, ASSIGNOR TO ADDOMETER CORPORATION, OF NEW YORK, N. Y., A CORPORATION OF DELAWARE.

ROLL-HOLDER FOR CALCULATORS.

1,158,453.

Specification of Letters Patent.

Patented Nov. 2, 1915.

Application filed May 4, 1915. Serial No. 25,668.

To all whom it may concern:

Be it known that I, WITSEL R. DE CAMP, a citizen of the United States, and a resident of Roseland, in the county of Essex and State of New Jersey, have invented certain new and useful Improvements in Roll-Holders for Calculators, of which the following is a specification.

This invention has for its object to provide an improved means for supporting a roll of paper of different widths at the rear of the carriage carrying the platen on a calculator, a typewriter, or any similar mechanism; and further to provide in connection therewith guiding means arranged to guide the paper from the roll onto the platen or printing surface.

In the accompanying drawing illustrating one embodiment of my invention, Fig. 1 shows in plan a carriage and platen at the rear of a printing machine, with a roll of paper supported thereby. Fig. 2 is a rear elevation of the parts shown in Fig. 1, with the roll removed and the arms in their folded position. Fig. 3 is a side elevation of the parts shown in Fig. 1, enlarged. Fig. 4 is an end elevation of one of the supporting arms with its attached guide bar; Fig. 5 is a vertical section enlarged on the line 5—5 indicated in Fig. 2, and Fig. 6 is a horizontal section on the lines 6—6 of Fig. 5.

In the drawings is shown a platen 6 suitably supported at the rear of a printing machine 7. The platen is carried by a carriage one of whose end members 8 is indicated in Fig. 3, and which are shown as connected by a plate 9. At the rear of the plate 9 is supported a bar 10, by its end portions, so that between the ends of the bar is free, as shown in Fig. 1. On the bar 10 slide a pair of blocks 12 composed of sheet metal plates having ears 13 at the top and bottom bent around the bar 10; and also ears 14 bent rearward at the top and bottom and containing vertical alining apertures. These blocks are slideable endwise along the bar 10, from the position adjacent the ends as indicated in Fig. 2, toward the middle of the bar. If desired a plate spring 15 may be inserted between the ears 13 and the inner face of the bar 10, as shown best in Fig. 6, to increase the friction and retain the blocks in desired positions along the bar 10 to which they may be moved. To each of these blocks 12 is pivoted an arm 16, shown as provided with

bent ears 17 and 18 at the lower end, that are perforated, and are inserted between the ears 14 of the block 12 with the perforations registering to receive a pivot pin 19. The latter forms a vertical axis for the arm 16, so that it can swing from a position extending rearward as indicated in Fig. 1, to a position lying substantially in the plane of the bar 10, as shown in Fig. 2, and indicated in broken lines at the left in Fig. 1. Each arm 16 on its inner face is provided with a lug 20, that when the arms extend rearwardly in parallelism as indicated in Fig. 1, project in alinement and serve to support a roll of paper 21. By sliding these blocks 12 carrying the arms along the bar 10, different widths of the roll 21 can be accommodated within a considerable range of sizes. A coil spring 25 is arranged around the pivot pin 19 in each block with its ends engaging the arm 16, and the block 12 respectively, that serve to swing the arms inwardly from the rearwardly extending position against the bar 10. But ears 26 are shown projecting from the blocks 12 to engage the arm 16 in the closed position. When the arms are swung outwardly perpendicular to the bar 10, a bent ear 27 on each arm 16 will engage the block 12 and limit the movement of the arm in this direction.

On each arm 16 is pivoted a guide bar 22 having a bent extension 23 provided with a lower curved edge 24. When the arms 16 are supporting the roll as shown in Figs. 1 and 3, the arms 22 are swung rearward and the curved edge 24 is brought to engage the platen 6, as indicated in Fig. 3. Since these guide bars are pivoted on the outer side of each of the arms 16, these bars 22 will engage the platen at each edge of the paper that is fed to the platen from the roll 21. When it is desired to remove the roll and use the platen without the same, the guide bars 22 are swung upwardly adjacent the arm 16, as indicated in broken lines in Fig. 2, and then the blocks 12 are moved outwardly near the ends of the bar 10, and then the arms 16 are swung inwardly into the vertical plane of the guide bar 10. Thereupon the guide arms 22 can be swung downwardly as shown in Fig. 2 and will be out of the way and not interfere with a sheet of paper being placed on the platen. By this arrangement it will be understood that a roll of paper of different

widths can be readily supported at the rear of the platen, and the web therefrom fed to the platen, and suitably guided by the guide bars; which engage the platen at each edge 5 of the paper. When it is desired to use a sheet of paper instead of the roll, it can be quickly removed, and the supporting arms together with the guide bars or arms are quickly swung to the rear and placed in a 10 position not to interfere with the free use of the paper.

Having thus described my invention, what I claim is:

1. In a calculating machine, the combination 15 with a carriage and a platen thereon, of a bar at the rear of the carriage forming a horizontal guideway, a pair of blocks slidably mounted on the guideway one each side of the middle portion, an arm hinged to 20 each said block, a lug on the inner face of each arm at its outer end, the blocks being slidable to permit the arms to extend transversely rearward in parallelism to support rolls of different widths, and a guide bar on 25 each arm arranged to extend to the platen to guide the paper as fed from the supported roll, the blocks being also slidable to re-cede from each other and permit the arms and guide bars to be folded to lie in the 30 plane of the guideway.

2. In a printing machine, the combination 35 with a carriage and a platen thereon, of a bar at the rear of the carriage forming a horizontal guideway, a pair of blocks slidably mounted in the guideway one on each side of the middle portion, an arm hinged to each block, a lug on the inner face of each arm at its outer end, the blocks being 40 slidable to permit the arms to extend transversely rearward in parallelism to support rolls of different widths, and a guide bar hinged to each arm to swing in the plane of the arm and to be brought over to the top of the platen when the arms support a roll 45 whereby to guide the paper as fed to the platen, the blocks being slidable also to re-

cede from each other and permit the arms to be folded inwardly to cause the arms and guide bars to lie in the plane of the said guideway.

50

3. In a printing machine, the combination with a carriage and a platen thereon, of a bar at the rear of the carriage, a pair of blocks each provided with bent ears forming a guideway engaging the bar to slide 55 thereon, each block also having a pair of apertured ears extending beyond the bar, a pair of arms each provided with a pair of apertured ears at one end portion arranged to engage said apertured ears, a pin connecting said ears to pivotally mount the arms on the blocks, each arm having a lug on its inner face at the free end, the blocks being slidable to permit the arms to extend rearward in parallelism to support rolls of 60 different widths, and springs on said pivoted members to swing the arms in against the bar when free from the roll.

60

4. In a printing machine, the combination with a carriage and a platen thereon, of a bar at the rear of the carriage, a pair of blocks each provided with bent ears forming a guideway engaging the bar to slide thereon, each block also having a pair of apertured ears extending beyond the bar, a pair 70 of arms each provided with a pair of apertured ears at one end portion arranged to engage said apertured ears, a pin connecting said ears to pivotally mount the arms on the blocks, each arm having a lug on its 75 inner face at the free end, the blocks being slidable to permit the arms to extend rearward in parallelism to support rolls of different widths, and springs on said pivoted members to swing the arms in against the bar when free from the roll, each arm having a bent ear to limit its outward movement, each block having a bent ear to limit the inward swing of the arm.
